ELECTRIC COMMUTATOR AND INTERRUPTER ACCORDING TO THE SPARK-NEGLECTING PRINCIPLE

Julius Frederik Georg Poul Hartmann,
Copenhagen, DenmarkApplication December 17, 1934, Serial No. 757,931
In Denmark December 22, 1933

9 Claims. (Cl. 175—364)

The invention relates to electric commutators and interrupters according to the spark-neglecting or spark independent principle with one or more conductive liquid jets, especially to a hydrodynamic system for use in connection with such apparatus. Generally speaking the apparatus in question is that in which the spark produced during the operation takes place between points substantially on the conductive liquid so that the 5 stationary parts of the apparatus are not corroded. The jet-wave commutator, the plate-jet commutator, the spiral-jet commutator and the jet-chain commutator may be mentioned as examples of commutators of this kind. Generally 10 the conductive liquid will be mercury. Concerning the apparatus mentioned reference may be had to the specifications of the U. S. Patents Nos. 1,306,335, 1,365,491, 1,578,287, 1,567,367, 1,664,031, 1,708,061, 1,851,704, 1,919,633 and 1,930,933, together with Jul. Hartmann: Mercury-jet commutation and its technical possibilities, "Engineering" Nov. 20, and Dec. 11, 1931.

By the practical use of mercury jet commutators according to the spark-neglecting principle, especially the above named jet-wave commutator, irregularities in the function of the commutator have been disclosed by working for some length of time, which has been found to be due to the depositing of a grey powder in the 15 interior of the apparatus, especially at the edge of the jet opening. A further examination has shown that this powder substantially consists of small balls of pure mercury covered with fine particles of mercuric oxide, preventing the uniting 20 of the mercury balls. Notwithstanding the presence in the electrode chamber of an inactive gas, usually hydrogen, which is constantly supplied from a store and kept under a weak overpressure 25 oxygen must therefore be present in the chamber. This oxygen unites with the mercury under the influence of the commutation spark thus forming the said mercuric oxide. Without the cooperation of the spark mercury, practically, is 30 not oxidized in contact with the air.

Experiments have shown that the appearance of oxygen in the electrode chamber, among other things, is due to the following causes:

The mercury moves in a circuit, being reconducted from the electrode chamber, that is by 35 means of a pump to the reservoir from which the jet is supplied. As during the passage from the electrode chamber back to the reservoir the mercury contacts with atmospheric air there is the 40 possibility that small amounts of the latter are

conducted through the jet conduit to the electrode chamber.

It is the purpose of the present invention to completely preclude this carrying along of atmospheric air.

Accordingly the invention generally consists in keeping the liquid circuit externally closed, and in everywhere keeping the free space of the circuit, that is, the part not filled out by liquid, filled by inactive gas. Practically, the gas will generally 10 be the same as that present in the electrode chamber.

Other features of the invention will appear from the following description in connection with the drawings, in which—

Figures 1-3 show various embodiments of mercury jet-commutators, schematically, the electrode and the magnet system together with other parts irrelevant to the invention having been omitted.

The apparatus shown in Figure 1 consists of an electrode chamber 10 made of steel-plate welded together. At the top the chamber is closed by a heavy insulating plate 11 fastened in a steel-frame 12, having a perpendicular flange 13 below 25 projecting into a groove 14 containing mercury, said groove being provided at the upper edge of the chamber. Laterally the chamber 10 is provided with a liquid lock 15, also containing mercury and serving as a safety valve, and a well 16 30 is provided at the bottom of the chamber, in which well the mercury leaving the chamber is collected. This well is connected by a conduit 17 with the suction chamber 18 of a centrifugal pump 19 having a perpendicular shaft 20.

The shaft is surrounded by a casing 21 tightly connected to the pump house and forming at its lower part a narrow passage around said shaft so as to make a very narrow gap. During the working, the mercury level is as shown in the well 16 and the casing 21 so that a volume having a little free surface and not participating in the circulation produced by the pump is separated from the main part of the mercury in the casing 21. Substantially the same volume of mercury 45 will therefore constantly be present in the casing 21. This volume forms a lock between the external air and the liquid flowing in the circuit.

The pressure chamber 22 of the pump is connected by a conduit 23 with a tubular piece 24, in the uppermost part of which a partition 25 with an aperture is provided so that the mercury as shown passes the main part of the tubular piece as a continuous jet which below hits a bottom piece 26 inserted in the tubular piece so that the 55

jet is spread through apertures 27 in the side-wall of the tubular piece. The falling mercury is received in a container 28 surrounding the lower-most end of the tubular piece 24, the bottom of 5 said container being perforated so that the mercury now, as a shower of drops, falls further down to a reservoir 29, from which a jet conduit 30 leads to the chamber 10, the conduit 30 being carried airtight through the plate 11. At its top the 10 reservoir 29 supports a tubular piece 31, surrounding the space, through which the mercury drops are passing, and also the container 28, said piece being closed at its upper end by an insulating plate 32 through which the tubular piece 24 is 15 carried.

Below the partition 25 an inlet conduit 33 for inactive gas, as for instance hydrogen, is connected to the tubular piece 24, said gas passing through the piece 24 around the mercury jet and 20 through the apertures 27 to the container 28 where the space above the mercury is totally filled by the gas. From the bottom piece 26 a short tubular piece 34 open below leads through the perforated bottom of the container 28, said tubular 25 piece having openings 35, in its upper part through which the gas is conveyed to the chamber in which the mercury drops fall down.

From the reservoir 29 is branched an overflow passage 36, which is carried air-tight through 30 the plate 11. At the overflow passage 36 is provided an extension 37 containing a device corresponding to that constituted by the parts 24, 26, 25, 28, 34 and 35, and serving to produce a rain of mercury in the lowermost part of the extension 37, said mercury rain having also for its purpose to provide an electric interruption in the circulating current of mercury. At the end of the conduit 36 projecting into the chamber 10 said conduit is provided with an extension 38 having a 40 perforated bottom through which the mercury flows to the chamber 10, while the inactive gas which is carried along with the mercury escapes through openings 39 at the top of the extension 38. Both parts of the conduit 36 have such a diameter that the normal amount of overflowing mercury is not able to wholly fill out the conduit. The mercury therefor will carry with it bubbles of the gas so that the conduit acts as a pump for the gas.

50 A conduit 40 carried through the plate 11 is connected to the conduit 33 over a three-way cock 41 normally having the position I so as to conduct the amount of gas passing through the conduit 36 through the conduits 40 and 33 back to the tubular piece 24. In this manner an auxiliary circuit is provided for the inactive gas from the electrode chamber 10 over the reservoir 29 back to the electrode chambers 10 outside of the jet-conduit 30. The circulation of the gas in this circuit is effected 60 by the above-mentioned adaption of the overflow passage 36. When first the circuit is filled with inactive gas, the cock 41 has the position II. The gas then is supplied through a conduit 43, and the air in the circuit escapes through a nozzle 42. 65 The gas normally is supplied from a gasometer connected to the conduit 43. By normal operation this gasometer serves to maintain a constant over-pressure in the electrode chamber and the liquid circuit.

70 For commutating high tensions the inactive gas in the closed circuit may be kept under a considerable over-pressure. As, normally, the circuit including the chamber and pump will not everywhere be able to resist such a pressure, it may be 75 surrounded by a container in which substantially

the same pressure is maintained as in the circuit. Alternatively, the electrode chamber 10 with appurtenances (the parts 24, 30, 31, 33, 36 and 37) and the pump with driving motor respectively may be surrounded each by their own container with substantially the same pressure as in the circuit. However, this leads to constructions by which the active parts of the apparatus become difficult of access. More preferable embodiments are shown in Figures 2 and 3.

In Figure 2 the driving motor 51 of the pump 59 is surrounded by a dome 52, in which substantially the same pressure as in the circuit is maintained.

Thus it becomes possible, as in Figure 1, to 15 retain a free surface of mercury in the casing surrounding the pump shaft. The electrode chamber 10 is itself shaped as a cylindrical pressure container with curved bottom and cover. The cover is made of steel-plate and provided with tubular 20 insulators 53 where it is necessary. The remaining parts of the circuit will, without particular measures, be able to resist a considerable pressure.

Figure 3 as compared with Figure 2 shows that 25 the insulating plate 11 used in Figure 1 is retained. In order to relieve the plate 11 of strains owing to the pressure in the electrode chamber 10, the plate is outwardly surrounded by a dome 54, in which the same pressure as in the closed circuit is maintained. In view of the mounting, 30 flange-couplings 55 are inserted in the conduits 30, 36 and 40, which flange-couplings are accessible through a door 56 in the dome 54.

The invention is not restricted to the embodiments shown, but the latter may be altered in 35 various respects without departing from the scope of the invention. Thus it is not important whether as a neutral gas a single gas or more gases in mixture are used, and different gases 40 may be used at different places in the circuit.

Having thus fully described my invention I 45 claim as new and desire to secure by Letters Patent:

1. For use in connection with electric communicators and interrupters according to the spark-neglecting principle a hydrodynamic system comprising a circuit for a conductive liquid, preferably mercury, including an electrode chamber and a reservoir for the conductive liquid, said circuit being externally closed and the free space thereof 50 being filled with an inactive gas, an auxiliary circuit for the said gas being provided from the electrode chamber over the said reservoir and back to the electrode chamber.

2. For use in connection with electric communicators and interrupters according to the spark-neglecting principle a hydrodynamic system comprising an externally closed circuit for a conductive liquid, preferably mercury, including an electrode chamber and a reservoir for the conductive 60 liquid, the free space of said circuit being filled with an inactive gas, said reservoir being provided with an overflow passage for surplus liquid, an auxiliary circuit for the inactive gas being provided including the said electrode chamber, the 65 reservoir and the overflow passage, said passage debouching in the free space of the electrode chamber and being adapted to circulate the said gas in the auxiliary circuit.

3. For use in connection with electric communicators and interrupters according to the spark-neglecting principle a hydrodynamic system comprising an externally closed circuit for a conductive liquid, preferably mercury, including a pump, 70 said pump being provided with a substantially 75

vertical shaft projecting outside the system, said shaft being surrounded by a casing tightly connected to the pump housing and forming at its lower part a narrow passage around said shaft 5 in order to separate out a liquid volume which does not participate in the circulation in the circuit and serving to seal said circuit against the external air.

4. For use in connection with electric commutators and interrupters according to the spark-neglecting principle a hydrodynamic system comprising an externally closed circuit for a conductive liquid, preferably mercury, the free space in the said circuit being filled with an inactive gas 10 at a material over-pressure, said circuit including a pump, a motor being provided for driving the pump, said motor being surrounded by a dome connected to the pump housing, and in which is maintained substantially the same pressure as in 15 the circuit.

5. For use in connection with electric commutators and interrupters according to the spark-neglecting principle a hydrodynamic system comprising an externally closed circuit for a conductive liquid, preferably mercury, including an electrode chamber composed of a main 20 part built as a pressure container and an insulating cover, the free space in the said circuit being filled with an inactive gas at a material over-pressure, said cover at its outer side being surrounded by a dome in which is maintained substantially the same pressure as in the said circuit.

6. For use in connection with electric commutators and interrupters according to the spark-neglecting principle a hydrodynamic system comprising a circuit for a conductive liquid, preferably mercury, confined by solid walls and including an electrode chamber and a pump outside said chamber, said liquid being separated 30 from the external atmosphere over a substantial part of the circuit by the walls of the circuit

only, an inactive gas being present in the electrode chamber, all parts of the circuit being closed and sealed from the exterior, and all spaces not occupied by the liquid being filled with inactive gas.

7. For use in connection with electric commutators and interrupters according to the spark-neglecting principle a hydrodynamic system comprising an externally closed circuit for a conductive liquid, preferably mercury, including 10 an electrode chamber and a pump outside said chamber, all spaces of the said circuit not occupied by the liquid being filled with an inactive gas subjected to a material pressure above atmospheric.

8. For use in connection with electric commutators and interrupters according to the spark-neglecting principle a hydrodynamic system comprising an externally closed circuit for a conductive liquid, preferably mercury, confined 20 by solid walls, including an electrode chamber and a pump outside said chamber, all spaces of said circuit not occupied by the liquid being filled with an inactive gas subjected to a material over-pressure, said circuit including the walls thereof 25 being at least partly surrounded by a separate container in which is maintained substantially the same pressure as in the circuit.

9. For use in connection with electric commutators and interrupters according to the spark-neglecting principle a hydrodynamic system comprising an externally closed circuit for a conductive liquid, preferably mercury, confined 30 by solid walls including an electrode chamber and a pump outside said chamber, all free spaces 35 of the said circuit not occupied by the liquid being filled with an inactive gas at a material over-pressure, said electrode chamber being built as a pressure container.

JULIUS FREDERIK GEORG

POUL HARTMANN.
